UNITED STATES PATENT OFFICE.

LAURENCE VINCENT BENÉT AND HENRI ALBERT MERCIÉ, OF PARIS, FRANCE.

GUN-MOUNT.

1,089,307.

Specification of Letters Patent.

Patented Mar. 3, 1914.

Application filed June 9, 1913. Serial No. 772,620.

To all whom it may concern:

Be it known that we, LAURENCE VINCENT BENÉT and HENRI ALBERT MERCIÉ, citizens of the United States and France, respectively, residing at Paris, in the Republic of France, have invented certain new and useful Improvements in Gun-Mounts; and we do hereby declare the following to be a full, clear, and exact description of the invention, such as will enable others skilled in the art to which it appertains to make and use the same.

Our present invention relates to improvements in mounts for machine guns, and especially in mounts for small portable machine guns of the Benét and Mercié type, such, for instance, as described in the U. S. patents of Benét and Mercié gas operated guns #861939, granted July 30, 1907, and portable guns #959291, granted May 24, 1910. In such gun mounts it is essential that the apparatus be very light and also compact for transportation, quickly adjustable and readily attachable to or removed from the gun, so that the gun may be used either with the mount, or separate therefrom, and the parts may be readily assembled or disassembled as required. While such guns of this class are capable of being used from the shoulder, at the same time it is desirable to insure greater steadiness of aim and accuracy of firing that the gun be supported upon a suitable mount, and that suitable elevating and training gear may be provided whereby the well-known advantages of firing from a mount rather than from the shoulder are secured.

Our invention will be understood by reference to the accompanying drawings in which the same parts are indicated by the same reference symbols throughout the several views.

Figure 1 shows a side elevation of the gun and mount; Fig. 2 is a plan view of the mount with the gun removed therefrom; Fig. 3 shows a section through the spade and base of the elevating and training gear along the line 3—3 of Fig. 2, and looking in the direction of the arrows; Fig. 4 is a front view of the mount with the gun removed, part being shown in elevation and part in section along the line 4—4 of Fig. 1; Fig. 5 shows a section through the head of the mount with the muzzle of the gun barrel connected thereto, the latter being shown in dotted lines; Fig. 6 shows on a larger scale

the head of the mount with the socket in elevation; Fig. 7 is a plan view of the device shown in Fig. 6; Fig. 8 is a sectional elevation on a larger scale of the head of the 60 mount as seen from the front, the section being along the line 4—8 of Fig. 6; and Fig. 9 shows the upper portion of Fig. 6 on a larger scale.

A represents the gun having the stock a, 65 the shoulder rest a', and the pistol grip a".

The gun is provided with suitable elevating and training gear such, for instance, as are shown in the Benét and Mercié Patent #959291 aforesaid. Any suitable elevating 70 and training gear may be used if desired; and these, not being a part of our present invention, will not be specifically described herein.

The gun mount comprises a trail with two 75 legs hinged thereto, a housing connected to trail and legs, and a socket piece to which the muzzle of the gun is detachably connected. The trail may be of any desired 80 shape and consists preferably of two cheeks, in the form of U-shaped metal plates 1, secured together as by the rods 2, and secured at their front ends to the housing 3. The rear end of the trail carries the shoe 4 to which is attached the spade 5. This shoe 85 4 is provided with side flanges 6 which serve not only to stiffen the sides of the shoe but also to act as guides for the feet 7 of the elevating gear 8, thus permitting the said elevating gear a slight longitudinal move- 90 ment relative to the shoe 4 as the gun is ele- vated or depressed.

The front end of the housing 3 has sleeves 10 projecting downwardly therefrom, in which is swiveled the tube 11, the ends of 95 which tube are slotted as at 12 to receive the ends 13 of the tubular legs 14 and 14', which legs are connected together by a hinged separator composed, for instance, of two links 15 hinged together as at 16 and 100 provided with outwardly-extending arms 17 adapted to engage the lugs 18 and to ordinary form a rigid brace; or to be bent or "broken" when it is desired to fold the legs along the barrel as shown in dotted lines in Figs. 1 and 2. Each of these legs is preferably provided with a spade or holding blade 19, and with a shoe 20 hinged thereto as at 21. The upper ends of the legs 14 and 14' are provided with arms 13 105 having inwardly projecting teeth 22 ar- ranged in the arc of a circle to engage the

corresponding teeth 23 of the segmental rack 24. By bending the joint 16 of the separator, the teeth 22 will become disengaged from the teeth 23 on the racks 24, and the said legs may be swung about the horizontal axis 11 raising or lowering the said axis, and correspondingly raising or lowering the pivotal support for the muzzle of the piece.

10 The housing 3 has swiveled therein the yoke 30, the two parts being preferably connected together by means of the screw-threaded connection 31 (see Figs. 4, 5 and 8), and the lower end of the yoke resting 15 on suitable spring washers 32. The arms 33 of this yoke are provided with trunnion seats 34 in which are swiveled the trunnions 35 of the cradle 36 supporting the muzzle of the gun. This cradle is provided with a 20 cover 37 hinged to the cradle as at 38. An overhanging arm 39 of said cover is provided with a casing 40 in which is mounted a spring lock 41 adapted to engage in a notch 42 in the trunnion 35, as shown in 25 Figs. 6 and 9. This spring lock is provided with a handle 43, so that it may be withdrawn and disengaged from the trunnion when it is desired to lift the hinged cover.

The front end of the barrel is provided 30 with annular notches 44 to engage the annular ribs 45 in the cradle and 46 in the cover, as shown in Figs. 5 and 8, whereby the gun is locked to the mount against recoiling thereon.

35 The yoke 31 will permit the gun to be swung through an angle laterally about the muzzle pivot, while the cradle 36 will permit it to be swung through the desired angle in elevation, about the muzzle pivot, and 40 thus a universal joint for the barrel supporting head is provided.

The line 50 (see Fig. 1) indicates the maximum angle of elevation of the gun relative to the level of the ground; and the line 45 51 indicating the maximum angle or depression of the gun relative to the level of the ground, which is indicated by the shaded portion 52 of Fig. 1.

If desired, the gun may be fired from the 50 shoulder, without using the elevating and training gear, as fully described in connection with our Patent 959291 aforesaid. The gun may be readily removed from the gun mount, by disengaging the spring lock 41 55 and swinging the cover 37 clear, and then lifting the muzzle of the gun out of engagement with the cradle, while the parts may be readily restored to the initial position by reversing this operation. It will be noted 60 that the front legs 14 and 14' may be quickly and readily moved to the desired angle of inclination as hereinbefore described, thus varying the height of the muzzle pivot; or when not in use the said legs may be swung 65 alongside the cheeks of the trail, as shown

in dotted lines in Figs. 1 and 2, and then secured in position as for purposes of transportation. Thus it will be seen that the gun may be employed entirely independently 70 of the mount, or it may be used mounted thereon, and fired therefrom as hereinbefore described.

By having the gun pivot at or near the muzzle, it will be obvious that a slight displacement either in train or in elevation at 75 the breech would cause less error in the line of fire than if the gun were trunnioned farther in the rear, or especially near the breech, as is generally the case with heavy ordnance. One advantage of this arrangement is that more movement is permitted to the breech of the gun either in elevation or train to vary the direction of the line of fire without throwing it much off the target. This is especially important in the quick 80 manual control to which such guns are ordinarily used. Another advantage of this arrangement is that the strain from the recoil being thrown on the barrel supporting head, is transmitted at a small angle only, or almost in a straight line to the spade 5, thus 85 reducing to a minimum the vibrations of the gun, and lessening the shock on the shoulder of the gun servant.

It will be obvious that various modifications might be made in the herein described apparatus, and in the construction, combination and arrangement of parts which could be used without departing from the spirit of our invention.

Having thus described our invention what we claim and desire to secure by Letters Patent of the United States is:—

1. The combination with a gun mount provided with a trail and housing, two front legs hinged to said housing and adapted to be swiveled about a horizontal axis therein, the said housing and said front legs being provided with engaging rack teeth, a swiveled head carried by said housing, a gun, and means for detachably connecting said gun near the muzzle to said swiveled head, substantially as described.

2. The combination with a gun mount provided with a trail and housing, two front legs hinged to said housing and adapted to be swiveled about a horizontal axis therein, the said housing and said front legs being provided with engaging rack teeth, a hinged separator adapted to separate said front legs, a swiveled head carried by said housing, a gun, and means for detachably connecting said gun near the muzzle to said swiveled head, substantially as described.

3. The combination with a gun mount provided with a trail and housing, two front legs hinged to said housing and adapted to be swiveled about a horizontal axis therein, the said housing and said front legs being provided with engaging rack teeth, a swiv-

- eled head carried by said housing, a gun, and means for detachably connecting said gun near the muzzle to said swiveled head, with means for vertically moving the breech 5 of said gun, substantially as described.
4. The combination with a gun mount provided with a trail and housing, two front legs hinged to said housing and adapted to be swung about a horizontal axis therein, 10 the said housing and said front legs being provided with engaging rack teeth, a hinged separator adapted to separate said front legs, a swiveled head carried by said housing, a gun, and means for detachably connecting said gun near the muzzle to said swiveled head, with means for vertically moving the breech of said gun, substantially as described.
5. The combination with a gun mount 20 provided with a trail, two front legs hinged to said trail and adapted to be swung about a horizontal axis and fixed in the desired position, a housing carried by the head of said trail and provided with interior screw threads therein, a swiveled head carried by said housing and provided with exterior screw threads engaging those in the housing, a gun, and a cradle carried by said swiveled head for detachably connecting said gun near the muzzle to said swiveled head, substantially as described.
6. The combination with a gun mount provided with a trail, two front legs hinged to said trail and adapted to be swung about 35 a horizontal axis and fixed in the desired position, a housing carried by the head of said trail and provided with interior screw threads therein, a swiveled head carried by said housing and provided with exterior screw threads engaging those in the housing, a gun, and a cradle carried by said swiveled head for detachably connecting said gun near the muzzle to said swiveled head, with means for moving vertically the breech 40 of said gun, substantially as described.
7. The combination of a gun mount provided with a head comprising a housing provided with interior screw threads therein, a yoke mounted on said housing and provided with exterior screw threads engaging 50 those in the housing, a cradle journaled in said yoke, a gun, and means for detachably connecting the barrel of said gun near its muzzle to said cradle with means for vertically moving the breech of said gun, substantially as described.
8. The combination with a gun, of a gun mount provided with a head comprising a housing provided with interior screw threads therein, a yoke mounted on said housing, a cradle journaled in said yoke, a hinged cover for said cradle, and a spring lock carried by said cradle and positively locking 60 said cover, substantially as described.
9. The combination with a gun, of a gun mount provided with a head comprising a housing, a yoke mounted on said housing, a cradle journaled in said yoke, a hinged cover 70 for said cradle, and a spring lock for said cover comprising a coil spring and a plunger adapted to positively lock said cover to said cradle, substantially as described.
10. The combination with a gun, of a gun 75 mount comprising a housing provided with internal screw threads therein, a trail secured to said housing, front legs adjustably hinged to said housing, a yoke provided with exterior screw threads engaging those in 80 said housing, and a cradle journaled in said yoke, substantially as described.
11. The combination with a gun, of a gun mount comprising a housing provided with internal screw threads therein, a trail secured to said housing, front legs adjustably hinged to said housing, a yoke provided with exterior screw threads engaging those in 85 said housing, a cradle journaled in said yoke, a hinged cover for said cradle, and a spring lock for said cover comprising a coil spring and a plunger adapted to positively lock 90 said cover to said cradle, substantially as described.

In testimony whereof, we affix our signatures, in presence of two witnesses.
